UNITED STATES PATENT OFFICE.

JOSEPH E. BARKER, OF DENVER, COLORADO.

PERMUTATION DOOR LOCK.

Application filed April 10, 1923. Serial No. 631,062.

To all whom it may concern:

Be it known that I, JOSEPH E. BARKER, a citizen of the United States, residing at Denver, in the city and county of Denver 5 and State of Colorado, have invented certain new and useful Improvements in Permutation Door Locks; and I do declare the following to be a full, clear, and exact description of the invention, such as will 10 enable others skilled in the art to which it appertains to make and use the same, reference being had to the accompanying drawings, and to the characters of reference marked thereon, which form a part of this 15 specification.

This invention relates to permutation locks and has special reference to a door lock of this type.

It is the object of this invention to produce a keyless door lock which shall be of 20 simple and substantial construction, and which shall be positive in its action, and which shall be easily operated.

It is a further object of this invention to produce a lock that shall be of neat appearance and which shall be so constructed that the combination can be readily altered and in which the combination can be readily ascertained whenever the door is open.

The above and other objects, that will be 30 readily apparent as the description proceeds, are attained by means of a construction which will be hereinafter described in detail, reference being had for this purpose 35 to the accompanying drawings in which the preferred form of my improved lock is shown, and in which:

Fig. 1 shows an outside elevation of a portion of a door with my lock in place 40 thereon.

Fig. 2 shows an inside elevation of a portion of a door which is equipped with my lock.

Fig. 3 is a view looking at the door edge- 45 wise, as indicated by the arrow 3 in Fig. 1.

Fig. 4 is a side elevation of the lock with the locking means removed, said view showing the surface along line 4—4, Fig. 6.

Fig. 5 is a section taken on line 5—5, 50 Fig. 6.

Fig. 6 is a section taken on line 6—6, Fig. 5.

Fig. 7 is an end elevation of the lock looking in the direction of arrows 7—7, Fig. 5.

Fig. 8 is a section taken along line 8—8, 55 Fig. 5.

Fig. 9 is a view looking in the direction of arrow 9, Fig. 10 and shows the position of the parts when the bolt is withdrawn or in 60 unlocking position.

Fig. 10 is a section on line 10—10, and shows the parts in the position corresponding to Fig. 9.

Fig. 11 is a view of the locking device looking in the direction of the arrow 11 in 65 Fig. 12; and

Fig. 12 is a side elevation of the locking device.

The same reference characters will be used to designate the same parts through- 70 out the several views.

Numeral 1 designates a door which is mortised for the reception of my improved lock. My lock is contained in a metal casing 2 which is approximately of the same 75 size and shape as that used in connection with ordinary key locks. The sides, indicated by numerals 3 and 4, are removable. The former will be designated as the top and the latter as the side of the lock. Secured to the bottom of the casing by means of a screw 5 is a stud 6, the purpose of which will hereinafter appear, and in the corners near the removable side 4 there are blocks 7 to which the side 4 is secured by 80 means of screws 8. These blocks are also provided with openings 9 for the reception of screws used for holding the top in place. The bottom 10 is provided with an opening 11 for the reception of the hub 12 of the 90 cam 13 which has a square opening for the reception of the rectangular part 14 on the spindle portion 15. The cam 13 cooperates with the inwardly projecting lugs 16 on the ends of the U-shaped part 17 of the bolt 95 18 in the manner common in locks. When the spindle 15 is rotated, it will rotate the cam 13 and this in turn will withdraw the bolt or move the same inwardly against the tension of the spring 19 which surrounds the guide rod 20, which has one end fastened to the bolt 18 and the other slidably in an opening 21 in the stud 6. The purpose of the spring 19 is to keep the bolt 18 projected and the cam 13 in the position 100 shown in Fig. 5. The spindle is made of two relatively movable parts, 15 and 22. The part 22 is square, with the exception of a portion 23 near its inner end which is cylindrical and hollow. An opening 24 is 105 cut in the wall of the cylindrical portion 23. This opening extends about 84 degrees.

The part of the spindle indicated by numeral 15 is round, except for the square part 14 above referred to. The inner end of part 15 fits into the cylindrical opening in the part 23 and a pin 25 passes through the opening 24 and into the inner end of part 15. This pin holds the two parts together and also limits the relative rotary movement to approximately 84 degrees. The part 15 is 10 provided with a portion 26 of substantially the same diameter as the part 23. The top 3 has two openings 27 and 28, the former being for the reception of the hub 29 of the cam 30 which cam has a square opening for 15 the reception of the spindle portion 22. Slidably mounted on the spindle between the cam 13 and the cam 30 is a cooperating cam 31 which has cam surfaces that cooperate with similar cam surfaces on the cam 20 30. Means, to be hereinafter described, serve to prevent rotary movement of the cam 31. A spring 32 is interposed between the cams 13 and 31 and serves to hold the three cams 13, 31 and 30 in place. It is evident that 25 the spring 19, acting through parts 17, 16 and 13 will normally retain the spindle part 15 in a definite position, but since there is about 82 degrees of relative rotary movement permitted between the parts 15 and 22, 30 it is evident that other means must be provided to bring the part 22 back to normal position and for this purpose I have provided the following mechanism:

The cam 30 is provided with a radial pin 35 33 provided at its outer end with an opening to which the end of a spring 34 is attached. The other end of spring 34 is anchored to a pin 35 and is tensioned. It is evident that the spring 34 will tend to hold the cam 30 40 in such a position that the axis of the spring passes through the center of the spindle 22, and that when the latter is rotated, the cam will also rotate and stretch the spring, which will return these parts to their normal position as soon as they are released. When the parts 15 and 22 are in their normal at rest position the pin 25 will occupy a 45 position midway between the ends of the slot or opening 24 so that spindle part 22 can be rotated in either direction about 42 degrees without moving the part 15 and conversely part 15 may be rotated through an angle of approximately 42 degrees without rotating the part 22. Whenever part 50 15 is rotated approximately 42 degrees in either direction, the cam 13 operates to retract the bolt 18. The spindle part 15 is always on the inside of the door so that the lock can always be opened from the inside, 55 whether it is locked against opening from the outside or not. One arm of the U-shaped member 17 has a projection 36 on its outer side. A night latch slide 37 has a notch 38 on one side. This notch is adapted 60 to receive the projection 36. The slide 37 is

movable towards and away from the projection 36 and is held in place by a plate 39. A pin 40 is secured at one end to the slide 37 and serves as the means by which the latch is moved into and out of operative 70 position. If the parts occupy the position shown in Fig. 5 and the catch is moved into engagement with the projection 36, it is evident that the bolt 18 cannot be moved in either direction. 75

I will now describe the means which I have provided for locking the bolt so that it may not be retracted by a rotation of the spindle part 22 or which, more correctly speaking, will lock the spindle part 22 80 against rotation. The cam 31 has formed integral therewith a radially extending portion whose outer end is preferably rounded, as indicated by the numeral 42. Surrounding the edge of opening 28 on the inside of 85 the removable top piece 3, is a flange 43 whose ends 44 terminate near the sides of the portion 41 and serve as a means for preventing rotation of the cam member 31 which is therefore forced to reciprocate on 90 the spindle whenever the cam 30 is rotated.

It is now evident that if we can provide means whereby the cam 31 can be held against longitudinal movement, the spindle part 22 will then be locked against rotation, 95 and, as a result of this, the bolt 18 cannot be operated from the outside of the door. In order to control the movements of the cam 31, I provide a permutation locking means which is substantially the same as the 100 one described by me in my co-pending application, Serial No. 591,633, filed September 30, 1922, of which application this case is a continuation in part.

My locking means consists of a cylindrical 105 metal part 45 which fits within the hole 28. Secured to the rear of the part 45 are a plurality of tumblers 46, three being shown in the drawing, which may all be exactly alike and each provided with a hub 47 which serve to space the tumblers apart, or the hub may be omitted on the innermost disk, as shown on the drawing, as this will save a little space. The tumblers 46 have each 110 a central opening and are rotatably held in place by a tubular pivot bolt 48 whose end is threadedly connected to the part 45 (Fig. 8). Each tumbler has its periphery formed into gear teeth and at one point in the periphery of each tumbler there is an arcuate 115 notch 49 (Fig. 11). These notches are of substantially the same curvature as the end 42 of the part 41 and the tumblers are so located on the part 45 that the notches 49 partly surround the curved end 42 of member 41. In order that the tumblers may be rotated from the position shown in Fig. 10, the projecting portion 41 must be provided with notches 50 which are in the same plane 120 as the tumblers when the parts are in their 125 130

normal position (Figs. 7 and 8). The notches 50 are of such depth that the tumblers may be readily turned to any desired position. When one or more of the tumblers are rotated so as to bring a solid portion into one of the notches, it is evident that the cam 31, which is integral with the part 41, cannot be moved longitudinally on the spindle and therefore the spindle part 22 will be locked against rotation for reasons that are perfectly obvious from an inspection of Figs. 7, 8 and 9. When the tumbler is again rotated to a position in which the notch 49 registers with the curved end 42, the cam 31 can move longitudinally to the position shown in Fig. 9. The tumblers 46 are rotated by means of pinions 51, the outermost one of which is connected to a tubular member 52, the intermediate one being likewise connected to a similar tubular member 53, while the outermost pinion is secured to the end of a rod 54. The pinions each mesh with the corresponding gear wheel 46 and can each be rotated by turning the corresponding knob 55. On each side of the pinions 51, there are studs 56 and 57 to the former, of which a number of pins 58 are secured. These pins are so located that they project over the edges of the pinions and form stops which are engaged by the projecting portions 59 which are secured to the pinions. The stud 57 has a hole 60 corresponding to each pinion and in each hole there is a spring 61 and a steel ball 62. The balls cooperate with the gear teeth on the pinion and form detents which serve to produce sufficient retarding action to keep the pinion from being rotated through friction, and they also serve as means by which the operator can determine the number of teeth that the pinions and the tumblers have been rotated.

The combination can be set to any desired number by removing the tumblers, setting the pinions any desired number of notches from the zero position, where part 59 engages the pins 58, and then replacing the tumblers with the notches 49 in line with the corresponding arcuate notch in the member 45. The locking assembly shown in Figs. 11 and 12 is secured in place by means of a bolt 64 which engages the threaded interior of the pivot pin 48.

The side 4 has been made readily removable so that the occupant of the house, or the owner, can remove the same for the purpose of determining the combination, as it may happen that the combination has been forgotten or has been changed by the tenant. This is of great importance for the reason that unless the tumblers are in unlocking position, the locking device (Figs. 11 and 12) cannot be removed, even when the bolt 64 is taken out.

Plates 66 and 39 have their edges pro-

jecting over the arms of the U-shaped member 17 and serve as guides for the latter.

From the above, it will be apparent that I have produced a combination lock that is of simple and substantial construction, which can be readily operated and which has a pleasing appearance.

Having now described my invention, what I claim as new is:

1. A lock comprising, in combination, a casing; a bolt slidably mounted in said casing and adapted to have a portion thereof projecting through the side of the casing; means comprising a spring for normally holding the bolt in projected position; a two-part spindle extending through said casing; a cam non-rotatably mounted on one part of the spindle, said cam having means for engaging the bolt and for retracting it whenever the cam is rotated in either direction, the two parts of said spindle being connected by a lost motion means that permits the two parts of the spindle to rotate a predetermined amount with respect to each other; a second cam member non-rotatably mounted on the other part of the spindle, said cam having cam surfaces on one side thereof; a member slidably mounted on the spindle between the two cams, said member having cam surfaces on one side adapted to cooperate with the surfaces of the cam; means comprising a spring for yieldingly holding one cam surface against the other; means for preventing rotation of said member; and means for locking it against longitudinal movement.

2. In combination, a spindle; a cam non-rotatably mounted thereon, said cam having one side thereof provided with cam surfaces; a member rotatably and slidably mounted on the spindle, said member having cam surfaces engaging the cam surfaces of the cam; means comprising a spring for holding the cam surfaces together; means for preventing the rotation of said member whereby when the cam is rotated the member will be moved longitudinally on the spindle; and means for locking said member against longitudinal movement.

3. In combination, a spindle; a cam non-rotatably mounted thereon, said cam having one side thereof provided with cam surfaces; a member rotatably and slidably mounted on the spindle, said member having cam surfaces engaging the cam surfaces of the cam; means comprising a spring for holding the cam surfaces together; means for preventing the rotation of said member whereby when the cam is rotated the member will be moved longitudinally on the spindle; and means for locking said member against longitudinal movement, said means comprising a plurality of permutation tumblers.

4. A lock comprising a spindle formed of

- two parts, said parts being relatively rotatable to a limited extent; a cam non-rotatably connected to one of said parts; a second cam non-rotatably connected to the other part, said first named cam having means for withdrawing a bolt whenever it is rotated in either direction, the second cam having cam surfaces on one side; means comprising a spring secured to the second cam 5 for holding it in a predetermined position; a locking member slidably and rotatably mounted on the spindle between the two cams, said member having cam surfaces for cooperating with the corresponding cam surfaces on the second cam; a spring intermediate the first mentioned cam and the locking member, said spring being under compression whereby the cam surfaces of the locking member will be yieldingly held against the cam surfaces of the cam member; means 10 for holding the locking member against rotary movement; and means comprising a plurality of tumblers for locking said locking member against longitudinal movement.
- 25 5. A combination lock comprising a base member; a plurality of tumblers rotatably mounted thereon, said tumblers having their edges provided with gear teeth; a notch in the edge of each tumbler; a plurality of pinions meshing with the gear teeth of said tumblers; means for rotating each pinion separately; stop means for limiting the rotary movement of said pinions; and a spring 30 detent cooperating with the teeth of the pinions.
- 35 6. A combination lock comprising a base member; a plurality of tumblers rotatably mounted thereon, said tumblers having their edges provided with gear teeth; a notch in the edge of each tumbler; a plurality of pinions meshing with the gear teeth of said tumblers; means for rotating each pinion 40 separately; stop means for limiting the rotary movement of said pinions, and a spring detent cooperating with the teeth of the pinions.
- separately, said means comprising a plurality of concentric relatively rotatable shafts; stop means for limiting the rotary movements of said pinions; and a spring 45 detent for cooperating with the teeth of said pinion.
7. A combination lock comprising a base member, a plurality of disklike tumblers rotatably mounted thereon, said tumblers being provided with gear teeth, a notch in the edge of each tumbler, a plurality of pinions meshing with the gear teeth of said tumblers, means for rotating each pinion separately, stop means for limiting the rotary movement of said pinions, and a spring 50 detent cooperating with the teeth of the pinions.
- 55 8. A permutation lock comprising a base member, a locking bolt slidable thereon, means operatively connected to the bolt for reciprocating the same, means for rendering said bolt reciprocating means inoperative, said means comprising a cam member operatively connected to the reciprocating means, a slidable member operatively connected to the cam and adapted to be reciprocated by the cam, means for locking said slidable member against longitudinal movement, said means comprising a plurality of rotatable members having gear teeth, the outer edges of said members having notches adapted to cooperate with said slidable member, a plurality of pinions meshing with the 60 gear teeth on the rotatable members, means for rotating each cooperating pinion and rotatable member separately, stop means for limiting the rotary movements of said pinions, and a spring detent cooperating with 65 the gear teeth.
- 70 In testimony whereof I affix my signature.
- 75 JOSEPH E. BARKER.
